CLAIM

The ornamental design for a telephone main frame module or similar article, as shown.

DESCRIPTION

FIG. 1 is a front, top and right side perspective view of a telephone main frame module or similar article; FIG. 2 and 3 are respectively top and bottom plan views thereof;

FIG. 4 is an elevational view as seen from the left hand side of FIG. 1 thereof;

FIG. 5 is a left side elevational view thereof.

The broken line showing of horizontal members in FIGS. 1, 2, 3 and 5 is for illustrative purposes only and forms no part of the claimed design.

FIG. 1

FIG. 2

FIG. 3

FIG. 4

FIG. 5
